NEWSPAPER VENDING MACHINE
George H. Vaara, 12550 9th NW, Seattle, Wash. 98146
Filed Apr. 13, 1965, Ser. No. 447,722
16 Claims. (Cl. 194—88)

This invention relates to a machine for vending newspapers or like articles one by one, preferably wholly by mechanical means. The reference hereinafter to newspapers will be understood to include like articles, such as magazines, for instance.

The machine embodying the invention in its preferred form includes shelves arranged in a generally horizontal series, each capable of supporting a single paper that is held in an upright plane, and so mounted, preferably hingedly, that it will be held in horizontal supporting position by its individual shelf support, one of a series thereof, until the last support of the series advances past each given shelf in succession. Thereupon, the shelf having been removed by such swinging from beneath the next paper, that paper drops and is discharged. It is preferred that the supported papers be subjected at no time to a lateral force such as might drag the paper, or its lower edge, sidewise, and possibly cause it to jam the mechanism. To this end no part of its support should be located immediately beneath the paper, nor should the paper itself have any support other than a hinged shelf; furthermore, this shelf should be supported by mechanism offset laterally beyond the space through which the paper drops when its shelf swings down at delivery, wherefore there can be no obstruction to its delivery. The shelves do not advance, but the supports advance step by step, under control of any suitable coin mechanism, by a distance to deliver a single paper. In the preferred mechanical construction the shelf supports are arranged in two series, along an endless chain, with a gap between the last support of one series and the first support of the following series. When each gap stops beneath any given shelf, that shelf is unsupported, and swings downwardly about its hinge axis, along one edge. With a succeeding advance of the chain and its shelf supports, each previously downswung shelf is swung up to its supporting position, ready to receive another paper. Each advance of the chain and its shelf supports is accomplished manually, although under control of suitable coin mechanism.

It will be seen that such a machine involves no advance of a paper, with the possibility of fouling and tearing it, and is mechanically simple, and unlikely to become inoperative or to give mechanical trouble. It is self-contained, for it requires no electrical power source for its operation, the entire operation being mechanical. It can be ruggedly made, little subject to wear, and as for servicing, it requires only that each paper be partitioned off from other papers, at a given spacing. That spacing may be such that a daily paper, at say ten cents, or a Sunday paper, at for example, twenty-five cents, can be dispensed from the same machine, appropriate modification being made in the coin control, or any given machine may be used to deliver only one kind of paper. The accomplishment of these ends, and the provision of a reliable and relatively inexpensive vending machine, are the main objects of the invention, and other objects will appear as this description progresses.

The accompanying drawings show the invention embodied in a typical and preferred form, although it will be understood that changes may be made in its general form and arrangement, and in many of its details, without departing from the invention as claimed.

FIGURE 1 is a side elevational view of the operating mechanism, the near side of the casing being omitted.

2

FIGURE 2 is a transverse sectional view just inside the front of the casing.

FIGURE 3 is an isometric view of the mechanism that effects delivery of a paper.

5 FIGURE 4 is an isometric view of part of the coin mechanism, illustrating in particular how delivery of the last paper prevents acceptance of another coin.

This vending machine is intended to deliver newspapers, each in its characteristic flat, once-folded condition as it is delivered from the press. Magazines and like articles can be delivered by the same machine, without change other than adaptation for size, and use of coin mechanism to handle the requisite coin. The coin mechanism is not part of this invention, for any suitable coin mechanism can be used, and it is not shown in great detail.

The newspapers are arranged in the machine for delivery each in a generally upright plane, usually resting on its folded edge, the several planes being parallel. The manner in which this disposition is attained is not highly important; by way of example, the space within the casing 9 is partitioned by a series of parallel, upright partitions 91 into an appropriate number of newspaper spaces. Their spacing from one another may be only sufficient to receive the thickest paper intended to be vended; if 20 a given machine is intended to vend alternatively a daily edition and a Sunday edition, their spacing must be such as to accommodate the thicker Sunday edition. The coin mechanism must be appropriate to the edition being sold at any given time.

30 Each paper P is initially supported in its space between fixed partitions 91 upon a shelf 1, the latter so supported that it can move from its normal supporting position to a non-supporting position upon proper operation of the coin mechanism. Preferably each shelf 1 is hingedly supported by a transverse rod 10 along its one edge, which rod is pivoted in a wall 92 extending from front to rear within the casing 9, and in an opposite wall 93. Laterally outside the wall 92 the rod 10 is formed with a lever arm 11, with which is engaged a support such as is about to 35 be described. The hinged mounting described is a convenient and preferred one, but any mounting whereby the newspapers' immediate supports can be removed, one at a time, to non-supporting position, is sufficient to satisfy the broader aspects of the invention.

40 45 Each shelf 1 is supported at any given time (with the exception of the shelf that has just swung down to deliver a paper) by an individual support 2, of which there is a series, one for each shelf, positioned beneath the lever arm 11 of its shelf to hold the lever arm 11 and its shelf 50 in generally horizontal or supporting position. This series of supports is shiftable along the series of shelves and past all the partitions 91. When the machine is fully loaded all shelves are upheld in supporting position, and the final shelf support 2F is in position immediately behind the last or rearmost shelf. The ensuing advance of the series of shelf supports 2, through a distance corresponding to the width of a newspaper space, leaves the last shelf 1F unsupported, and it swings down under the weight of itself and its paper, allowing that paper to 55 drop down. Conveniently a chute 94 beneath all the papers receives the paper thus discharged, and conveys it by gravity to a delivery point, as the paper P1 in FIGURE 1 has been conveyed from the space S1. With each succeeding actuation of the vending machine the series 60 of shelf supports advances through the same distance, and the final shelf support 2F leaves the next shelf and its lever arm 11 unsupported, and effects delivery of the rearmost remaining paper.

The manner in which advance of the series of shelf 65 supports 2 is accomplished is not material to the broader aspects of the invention. Preferably they are carried by an endless chain 20, the upper run whereof is supported

70

along a straight line by a guide 29, and passing about idler sprocket wheels 21. The chain extends from front to rear at a level below the shelves 2, and wholly to one side thereof. So arranged there may be two alternative series of shelf supports, with a gap of the width of a newspaper space between the final support of one series and the first support of the next series. This arrangement permits one paper to drop when the gap, as in FIGURES 1 and 3, registers with an individual shelf. Moreover, as an active series of supports advances, the oncoming series also advances and restores each previously downswung shelf to its supporting position. By the time the last paper has been delivered the shelves are again in position to receive and support the next batch of papers. Otherwise it would be necessary to reverse the movement of the series of supports, and to restore the series of shelves to their supporting position.

Step by step advance of the supports is effected preferably by wholly mechanical manually operable mechanism. This includes a ratchet dog such as that shown at 3, guided for vertical movement in a T-head, and spring-urged downward into engagement behind a shoulder formed on each successive support 2. The T-head 30 is carried by a rod 31, guided at 32 for movement forwardly and rearwardly, and limited in the extent of its reciprocation by its engagement with a guide 32 acting as a stop. A compression spring 33 acts to return the T-head to its rearmost position, following its forward movement to advance the supports. The ratchet dog might be arranged elsewhere in the advancing mechanism, but the arrangement described is most direct.

Mechanism for effecting forward or advancing movement of the T-head 30 and rod 31 may be directly or indirectly connected to the rod. As shown, an actuating lever 4 is pivotally mounted at 40 at its lower end, and is connected at 43 to the rod 31. A second rod 41 is guided for reciprocation at 42, and is connected by link 44 to the upper end of actuating lever 4. A handle 45 upon the rod 41, externally of the casing 9, enables a purchaser to pull the lever 4 and rod 31 forwardly, as shown in dot-dash lines in FIGURE 1, which delivers a paper such as P1; release of the handle 45 allows spring 33 to return all parts to their initial position, the dog 3 then engaging behind the next support 2, ready for the next delivery.

Each delivery is permitted by suitable coin mechanism, and any suitable such mechanism may be employed; none is shown herein in detail. However, means must be actuated by the delivery mechanism to prevent acceptance of a coin after the last paper has been delivered. To that end a feeler 5 is pivotally mounted adjacent the last of the papers to be delivered—the forward-most paper. So long as that paper is within the machine, the feeler 5 remains depressed, but when that last paper has been delivered, it swings into the space just vacated, as is seen in FIGURE 4. Thereby a blocking element, such as a flexible rod or wire 50, guided at 51, moves lengthwise to block access of a coin C to the chute 60 that leads to the coin wheel 6, and diverts the coin to a return chute 61. The coin wheel 6 is on a shaft 62, whereon is a second wheel 63 that carries a stop pin 64. The latter is located to engage and prevent reciprocation of the extension of rod 31 in the actuating direction, by engaging a complementary stop 35 on the rod. Until the wheel 63 has rotated to remove the stop pin 64 from the path of the stop 35 the mechanism cannot be operated. Such rotation is under control of a coin-engaging wheel 6.

The machine is loaded by opening the top 99 and inserting single papers in the spaces between partitions 91. At this time the final support 2F should be in position to support the rearmost shelf 1, and each other shelf is supported by its individual shelf support. A purchaser inserts the appropriate coin in the coin mechanism, whereupon the wheels 6 and 64 rotate, and as the pur-

chaser pulls on handle 45 the shelf supports—not the papers—advance by a distance equal to one newspaper space. The final support 2F advances to support the next-to-rearmost shelf, and having been withdrawn from supporting position relative to the rearmost shelf, the latter swings down and delivers its paper. A second purchaser follows the same procedure, delivering the originally next-to-rearmost paper. The second series of supports, advancing with the first series, engages the lever arm 11 of the rearmost shelf with the first support of the second series, and restores that rearmost shelf to supporting position. This goes on until the last or foremost paper has been delivered, and when that occurs the feeler 5 swings up, and acceptance of further coins is barred until the machine has been refilled.

Since the gap between two shelf supports 2, the last support 2F of one series and the first 2A of the following series, must at the start of the operation be located immediately behind the rearmost shelf 1, in such position that the next advance of the chain 20 will advance the gap to register with that shelf, and since at the time the foremost paper is delivered the gap registers with the extreme forward shelf, and the following gap is consequently one space removed from its starting position, it is necessary to advance that following gap this one space, before a new series of papers can be delivered. This advance can be effected manually or otherwise, as by a wrench or other tool applied to the squared end 22 of a shaft whereon a sprocket wheel 21 is fixed, to turn the wheel by the correct distance. This would be done through the opened access door 95 by the attendant who refills the vending machine. The same result can be effected by providing a dummy shoulder 23 at the gap, engagement of which by the ratchet dog 3 will advance the chain 20 and supports 2 by one space.

Newspapers of different publishers may vary in width. To accommodate narrower papers, and to insure correct operation of the feeler 5, a filler 98 may be used at one or both ends of the foremost space. This accurately locates this one paper. Accurate location of the others is not material.

I claim as my invention:

1. A vending machine for newspapers or the like, comprising shelves individually pivotally mounted along one edge, and of a size to support the lower edge of an individual paper that is disposed in an upright plane, when the individual shelf is disposed horizontally, a lever arm disposed laterally beyond the edge of a paper thus supported, and operatively connected to pivot with each shelf from the shelf's horizontal supporting position to a downswung delivering position, shelf-supporting means also disposed laterally beyond a supported paper, in position to engage and initially support said lever arms in their horizontal disposition, means to advance said shelf-supporting means step by step past successive lever arms, to locate the supporting means successively in non-supporting position beyond the last shelf's lever arm, beyond the next to last, and so on throughout the series of lever arms, whereby successive shelves corresponding to such lever arms will swing down, and their supported papers will drop, clear of the shelf-supporting means.

2. A vending machine as in claim 1, including means to restore each lever arm and its shelf, following delivery of the shelf's paper, to its horizontal supporting position.

3. A vending machine for newspapers or the like, comprising shelves arranged initially in a generally horizontal series and each of a size to support the lower edge of an individual paper that is disposed in an upright plane, shelf-supporting means located initially to support all said shelves, means to advance said shelf-supporting means step by step with respect to individual shelves, to locate the supporting means successively in non-supporting position beyond the last shelf, beyond the next to last, and so on throughout the series of shelves, whereby to deliver successive individual papers, coin mechanism to

control said advancing means, a feeler engaging the last paper to be discharged, and held thereby from its normal position, and means interconnecting said feeler and said coin mechanism to block acceptance of a further coin upon release of the feeler by delivery of the last paper.

4. A vending machine as in claim 3, and a filler disposed in the last paper space in position to locate a narrow paper relative to the feeler.

5. A vending machine as in claim 3, said coin mechanism including a rotative wheel, and stop means interengageable between the same and the advancing means but removable by insertion of a coin, and a blocking means operatively connected to said feeler to block insertion of a coin following delivery of the last paper.

6. A vending machine for newspapers or the like, comprising a plurality of normally horizontal shelves each hingedly supported along one edge and arranged in a series to support successive papers, when the same are disposed in upright planes, along their lower edges, a lever arm operatively connected to each shelf, a series of shelf supports guided for advance along a path beneath said arms to support the corresponding shelves in their generally horizontal disposition until the last shelf support has advanced beyond each given shelf and its lever arm, and means to advance said shelf supports step by step with respect to successive shelves, to locate the last support in succession in non-supporting position beyond the last shelf and its lever arm, beyond the next-to-last, and so on throughout the series of shelves, whereby to deliver successive individual papers.

7. A vending machine as in claim 6, including a second series of shelf supports, the first whereof is spaced behind the last support of the first series, said two series of shelf supports being connected for conjoint advance, whereby the supports of the second series will restore the shelves to supporting position following delivery of a paper.

8. A vending machine as in claim 7, including an endless chain and supports therefor, the two series of shelf supports being mounted, in spaced relation, upon said chain.

9. A vending machine as in claim 1, including a series of fixedly positioned upright partitions above and spaced correspondingly with the series of shelves, to maintain individual papers in generally upright planes.

10. A vending machine for newspapers or the like, comprising shelves hinged along one edge and arranged in a generally horizontal series, and each of a size to support the lower edge of an individual paper that is disposed in an upright plane, an endless chain and supports for the same, located below the shelves, a series of shelf supports carried by said chain in position to support each one of said shelves in paper-supporting disposition, the series of shelf supports incorporating a gap which when disposed in registry with a shelf will permit that shelf to swing downwardly, and means to

shift the chain and its shelf supports along the series of shelves, and thereby to shift the gap into non-supporting position relative to successive shelves, for delivery of the individual paper supported thereon.

5 11. A vending machine as in claim 10, wherein the chain-shifting means includes a ratchet dog operatively engageable with the chain to advance it and its shelf supports and the gap, and means to advance said ratchet dog successively by the spacing of the individual shelves.

10 12. A vending machine as in claim 11, wherein each shelf support is formed with an abutment, and the ratchet dog engages successive abutments to advance the chain and associated elements.

15 13. A vending machine as in claim 11, including additionally a guide for the ratchet dog paralleling the chain, a manually operable plunger, means interconnecting the plunger and the guide for advancing movement of the latter upon manual operation of the plunger, and stop means to limit movement of the guide.

20 14. A vending machine for newspapers or the like, comprising shelves arranged in a generally horizontal series and each of a size to support the lower edge of an individual paper that is disposed in an upright plane, a series of shelf supports located initially to support each 25 its individual shelf in paper-supporting position, and each formed with an abutment, the series of shelf supports terminating in a final support initially beneath the rear-most shelf, a ratchet dog guided for reciprocation lengthwise of the series of shelf supports, in position to engage 30 the abutments of the shelf supports and to advance the latter by the space of one newspaper, and coin-controlled means to reciprocate said ratchet dog.

35 15. A vending machine as in claim 14, including an actuating rod guided for manual reciprocation, a lever operatively connected to said rod to be angularly swung by its reciprocation, an operative connection between said lever and the ratchet dog, and spring means to return parts after actuation to their normal positions.

40 16. A vending machine as in claim 7, wherein the two series of shelf supports are spaced to define a gap of a width to permit a given shelf to swing down when such gap registers with such given shelf and its support, and so to deliver the paper supported by such given shelf, the first of the following series of shelf supports serving to 45 restore such downswung shelf to supporting position when the shelf supports and the gap advance again.
